AUGUSTO E. MUELLER, OF SAN FRANCISCO, CALIFORNIA, ASSIGNOR OF ONE-HALF TO
EMIL POHLI, OF SAN FRANCISCO, CALIFORNIA.

ELEVATOR-CAR.

1,194,411.

Specification of Letters Patent. Patented Aug. 15, 1916.

Application filed August 3, 1915. Serial No. 43,367.

To all whom it may concern:

Be it known that I, AUGUSTO E. MUELLER, a citizen of Argentina, who have declared my intention of becoming a citizen of the 5 United States of America, residing at San Francisco, in the county of San Francisco and State of California, have invented certain new and useful Improvements in Elevator-Cars, of which the following is a 10 specification.

The present invention has for its object to provide a safety device for elevator cars, which can be actuated from within the car by the operator and passengers, so as to prevent 15 the car from dropping down in case of accident.

Another object of my invention is to provide a device that will act in a positive fashion and not be dependent upon springs.

20 A further object is to arrange the device so that overloading of the car will not be detrimental to the operation of the device, but on the contrary the effectiveness of which will be directly proportional to the 25 load, that is to say, of which the checking or braking action will be the stronger the more passengers there are in the car.

A still further object of my invention is to arrange the device so that it is easily accessible 30 for repairs or renewal of parts.

With these and other objects in view, my invention consists in the construction, arrangement and combination of parts as will be hereinafter more fully specified.

35 In the accompanying drawings, which form part of the specification and in which similar reference characters denote corresponding parts, Figure 1 is a front elevation of an elevator car equipped with my 40 new device; Fig. 2 is an enlarged side view of the car and of the new device; Fig. 3 is a vertical section of the car as seen in the direction of the arrows 3—3 in Fig. 1; Fig. 4 is a section on line 4—4 of Fig. 1; Fig. 5 45 is a section on line 5—5 of Fig. 1; Fig. 6 is a bottom view on the ceiling of the car showing a part of my device and Fig. 7 is a cross section through one of the pulleys, showing the winding of the cable thereon.

50 In the drawings 1 denotes the guide pieces of the elevator shaft on which the elevator car C travels up and down and from which the car is suspended in the usual manner by cables 2 carrying the counterbalancing 55 weights 3 and running over pulleys.

The car C has secured to its top 4 lateral pieces 5 which are connected by the cross bar 6 to which the cables 2 are fixed and by two parallel cross spindles 7 the ends of which are rotatively borne in said brackets. Each spindle carries two sets of pulleys 8 and 9, the pulleys 8 being arranged adjacent to the inner faces of the brackets and the pulleys 9 being arranged adjacent to the outer faces of the brackets.

55 Suspended within the car C from the ends 10' of two cables 10 is a framework 11 of light but strong material which normally is adapted to lie near the inner face of the top 4 or the ceiling of the car. The ends 10' 70 of the cables 10 are passed upwardly through perforations 4' in the top of the car and are wound around the corresponding inner pulleys 8 (Fig. 4) so that on the frame being pulled down the cables unwinding at 75 one end from one pulley and at its opposite end winding around the other pulley will revolve the spindles 7 and consequently the outer pulleys 9. Owing to the cable connection between the pulleys the latter will 80 move in unison with one another.

75 Fixed with one end to and wound around the outer pulleys 9 are cables 12 the opposite ends 12' of which are attached to lever arms 13 fulcrumed at 13' in the brackets 5. There 85 are four such levers, one opposite each outer roller, and each is extended on the other side of its fulcrum and formed to a toothed cam piece 13² forming a clutch.

80 Extending vertically through the elevator shaft and midway between each pair of clutch arms 13 on each side of the car is a rail 14 with the opposite surfaces of which the corresponding clutches are adapted to coöperate. These clutches are operated by 90 the pulling action exerted on the frame work 11 through the medium of the cables 10, pulleys 8 and 9 and cables 12. It is evident that the stronger the pulling action or the weight on the frame 11 the stronger the pressure of 95 the clutches 13 against the rails 14 and the more effectively will the descending movement of the car be checked.

100 For conveniently grasping the frame 11 in order to actuate the clutch arms 13 the former is provided with a number of hanger straps 11'. In rest position the frame is supported by two longitudinal rods 15 each provided with a number of fingers 15' and rotatively mounted in suitable bearings 15² 110

provided near the ceiling of the car. The fingers 15' are adapted normally to engage around the side edges of the frame 11 and hold it in position near the ceiling. Fulcrumed in the center of the frame 11, as at 11^a, is a bar 16 which normally is adapted to extend across the frame 11 engaging with its ends one of the fingers 15' of each rod and thereby locking the rods 15 in position.

10 One end of the bar 16 is connected by a wire 17 or the like to one of the straps 11', as at 11^a (Fig. 5) which is nearest to the stand of the operator. Ordinarily the frame 11 lies near the ceiling and is supported in that position by the fingers 15' which are held locked in horizontal position by the bar 16. The passengers may thus grasp and hang on to the straps 11' without actuating the clutches and find a good support during the 20 rapid travel of the car. In case of accident the operator can effect the release of the frame 11 from the supporting fingers 15' by pulling one of the straps 11' which will turn the locking bar 16 releasing the rods 15 which will be turned around disengaging their fingers 15' from the frame 11. The passengers on grasping and pulling the hanger straps 11' will in the aforescribed manner cause the clutch arms 13 to turn so 30 as to engage the rails 14 and to check the car and thus prevent it from dropping down. The stronger the pull on the straps the more effective will be the braking action of the clutches 13^a.

35 In order to enable the operator to stop the car or to release the clutches at any desired point, I provide the following mechanism: Extending centrally and vertically along the inner sides of the car are two bars 17 which 40 with their lower ends pass outwardly through the car and are connected by a cross bar 17^a extending over the outer face of the bottom 4^a of the car (Figs. 1, 3 and 4). These bars are supported to be movable in vertical direction and rest with the cross bar 17^a on springs 18 secured to the car (Figs. 3 and 4). The upper ends 17^a of these bars are formed 45 at their side surfaces to racks (Fig. 3). Projecting from the clutch arms 13 through 50 recesses in the brackets 5 are pins 19 which engage with their free ends grooves 20' made in arms 20. These arms are fulcrumed adjacent to the inner faces of the brackets 5 on the same axes as the clutch levers 13 and 55 are adapted by reason of the pin coupling to swing in unison with the said clutch levers. There are four levers 20 and each is formed with a toothed sector 20^a that constantly meshes with the rack 17^a of the side 60 bars 17 so that when the clutch arms 13 are moved to engage the rails 14 the gears or sectors 20^a will move the bars slightly upwardly.

65 A platform or treadle 22 is hinged on the bottom of the car, as at 22', and carries at

its free end a pin 23 which projects outwardly through a slot 4^a made in the bottom of the car to rest against the cross bar 17^a, connecting the bars 17 (Fig. 3). By stepping on the said treadle the operator will depress the bars 17 and through the racks 17^a transmit motion to sectors 20^a which accordingly will cause the clutches 13 to turn so as to release the rails 14. On releasing the treadle the springs 18 will bring 75 the parts to initial position.

It will be seen that the clutch or safety device is positively actuated and is not dependent upon the elasticity of the springs.

The new device may be used as a substitute for the hitherto used brakes, or as an auxiliary device and in the latter case may be readily applied to old elevator cars without requiring any material changes in the construction of the car.

What I claim and desire to secure by Letters Patent is:

1. In an elevator, the combination with the car, of a safety device therefor, comprising braking means and members serving normally as supports for the passengers and connected to said braking means to operate the latter in case of accident.

2. In an elevator, the combination with the car, of a safety device therefor, comprising braking means, members serving normally as supports for the passengers and connected to said braking means to operate the latter in case of accident and locking means for said members to normally hold 100 the same locked.

3. In an elevator, the combination with the car, of a safety device therefor, comprising braking means and actuating means therefor, including gripping members normally inoperative and serving as supports for the passengers.

4. In an elevator, the combination with the car, of a safety device therefor, comprising braking means, actuating means 110 therefor, including gripping members extending from the ceiling of the car to be within the reach of the passengers to operate said braking means by pulling thereon and locking means for normally locking 115 said gripping members in inoperative position so that the latter will serve as supports for the passengers without operating said braking means.

5. In an elevator, the combination with the car, of a safety device therefor, comprising braking means, and actuating means therefor, including a frame work suspended near the ceiling of the car and having gripping members normally inoperative and 125 serving as supports for the passengers.

6. In an elevator, the combination with the car, of a safety device therefor, comprising braking means, actuating means therefor, including a frame suspended near 130

- the ceiling of the car and having gripping members for the passengers to operate said braking means and locking means for normally locking said frame in inoperative position so that the gripping members will serve as supports for the passengers without operating the said braking means.
7. In an elevator, the combination with the car, of a safety device therefor, comprising braking means and actuating means therefor, including a frame work suspended near the ceiling of the car and having hanger straps normally inoperative and serving as supports for the passengers.
- 15 8. In an elevator, the combination with the car, of a safety device therefor, comprising braking means, and actuating means therefor, flexible means operatively connected to said checking means and a frame suspended from said flexible means near the ceiling of the car and having gripping members normally inoperative and serving as supports for the passengers.
- 25 9. In an elevator, the combination with the car, of a safety device therefor, comprising braking means, actuating means therefor, including gripping members extending down from the ceiling of the car to be within the reach of the operator and passengers to operate the said checking means by pulling thereon and locking means controlled from the operator's stand to normally lock the said gripping members in inoperative position so that the same will serve as supports for the passengers without operating the said braking means.
- 35 10. In an elevator, the combination with the car, of a safety device therefor, comprising braking means, actuating means therefor, including gripping members extending down from the ceiling of the car and to be within the reach of the operator and passengers to operate the said braking means by pulling action, a locking device for said gripping members to normally lock the said gripping members in inoperative position so that the same will serve as supports for the passengers without operating said braking means and a connection between one of the gripping members serving for the operator and the said locking device, so that by pulling the said gripping member the said locking device will unlock the said members to render the same operative.
- 45 11. In an elevator, the combination with the car, of a safety device therefor, comprising braking means, actuating means therefor including a vertically movable frame suspended near the ceiling of the car and having hanger straps to be within the reach of the passengers, and flexible connections between said frame and said braking means to transmit motion to the latter when said frame is pulled downwardly.
- 55 12. In an elevator, the combination with the car, of a safety device therefor, comprising braking means, actuating means therefor, including pulleys, cables wound around the same and having their ends passed into the car, a frame work suspended from the ends of said cables near the ceiling of the car and having gripping members to be within the reach of the passengers to operate the said braking means by pulling thereon.
- 70 13. In an elevator, the combination with guide rails extending through the elevator shaft and the car, of a safety device, comprising braking means, adapted to coöperate with said rails and supported on said car, and actuating means within the latter normally serving as supports for the passengers and adapted when operative and when pulled upon to operate said braking members in case of accident.
- 75 14. In an elevator, the combination with guide rails extending through the elevator shaft and the car, of a safety device, comprising braking levers fulcrumed to the car and adapted to coöperate with said rails and actuating means therefor, including cables, a frame work suspended from said cables near the ceiling of the car and having gripping members normally serving as supports for the passengers and adapted when operative and when pulled upon to operate said levers.
- 80 15. In an elevator, the combination with the car, of a safety device, comprising braking means, actuating means therefor, including a vertically movable frame suspended near the ceiling of the car and having gripping members to be within the reach of the passengers to operate said braking means in case of accident by pulling thereon, supporting means within the car to normally hold the said frame in inoperative position and a locking device on said frame for locking said supporting means and controlled from the operator's stand.
- 85 16. In an elevator, the combination with the car, of a safety device therefor, comprising braking means, actuating means therefor, including means extending from the ceiling of the car normally serving as supports for the passengers, and means at the operator's stand for releasing the braking means at any desired time.
- 90 17. In an elevator, the combination with the car, of a safety device therefor, comprising braking means, actuating means therefor, extending from the ceiling of the car to be within the reach of and controlled by the passengers, and a movable platform at the operator's stand operatively connected to said checking means for releasing the latter at any desired time.
- 95 18. In an elevator, the combination with the car, a safety device therefor, com-
- 100 105 110 115 120 125 130

- prising braking means, actuating means therefor extending from the ceiling of the car to be within the reach of and controlled by the passengers, and means for releasing 5 said braking means and comprising vertically movable members operatively connected to said braking means and a movable platform at the operator's stand for controlling said vertically movable members.
10. 19. In an elevator, the combination with the car, of a safety device therefor, comprising braking means, actuating means therefor, extending from the ceiling of the car to be within the reach of and controlled 15 by the passengers, and means for releasing said braking means and comprising vertically movable racks supported on said car, toothed sector arms meshing with said racks and operatively connected to said braking 20 means and a movable platform at the operator's stand for controlling the movement of said vertical racks.
20. In an elevator, the combination with the car, of a safety device therefor, comprising braking means, actuating means therefor extending from the ceiling of the car to be within the reach of and controlled by the passengers, and means for releasing the said braking means at any desired time 25 and comprising vertically movable spring actuated racks supported on said car, toothed sector arms meshing with said racks and operatively connected to said braking means and a movable platform at the operator's 30
- stand for controlling the movement of said vertical racks.
21. An elevator car, comprising cross spindles rotatively supported on top of said car, two sets of pulleys fixed on said spindles, cables running over the pulleys of one 40 set and connecting said spindles so as to turn in unison with one another, braking arms fulcrumed to the top of said car, cables running over the pulleys of the second set and connected to said braking arms, and a frame 45 suspended from the ends of the cables of the first named set of pulleys and located within and near the ceiling of the car, said frame being adapted to be controlled by the passengers and to operate the said braking means through the medium of said cables and pulleys by pulling on said frame.
22. An elevator car, comprising braking arms fulcrumed on top of the car, a passenger controlled frame suspended within and near the ceiling of the car and operatively connected to said braking arms, vertically 50 movable racks supported on the car, toothed sector arms meshing with said racks and connected to said braking arms and a movable platform in the car serving to operate said movable racks into inoperative position.
- 60 In testimony whereof I affix my signature in presence of two witnesses.
- AUGUSTO E. MUELLER.
